(57) **CLAIM**

The ornamental design for a UV gel light, as shown and described.

DESCRIPTION

FIG. 1 is a rear perspective drawing of the invention;

FIG. 2 is a top view of the invention;

FIG. 3 is a rear view of the invention;

FIG. 4 is a bottom view of the invention;

FIG. 5 is front view of the invention;

FIG. 6 is a left side view of the invention; and,

FIG. 7 is a right side view of the invention.

The cord in FIGS. 1-4 and 6-7 is shown broken away to show indeterminate length and for ease of illustration.
